EUGENE N. STROM, OF CHICAGO, ILLINOIS, ASSIGNOR TO PETTIBONE, MULLIKEN & CO., OF CHICAGO, ILLINOIS, A CORPORATION OF ILLINOIS.

RAILWAY-FROG.

No. 888,203.

Specification of Letters Patent.

Patented May 19, 1908.

Application filed March 12, 1908. Serial No. 420,618.

To all whom it may concern:

Be it known that I, EUGENE N. STROM, a citizen of the United States, residing at Chicago, in the county of Cook and State of Illinois, have invented a new and useful Improvement in Railway-Frogs, of which the following is a specification.

My invention relates, particularly, to the so-called "heel-riser" in a railway-frog, and my object is to provide a novel construction thereof which shall materially simplify its manufacture and render it stable and secure in its operative position.

The element in a railway-frog which is known as the heel-riser is that part which is confined in the tapering space between the rails forming the frog-point to extend inward from the heel-portion of the frog and has its end adjacent to the heel-portion beveled downwardly on its top-surface to gradually guide the wheels of the rolling-stock, peripherally concaved by wear, upon the main rails of the frog in a manner to avoid pounding against the said end. A usual construction of the device upon which, more especially, my invention is designed to afford an improvement, consists of a railway T-rail confined in inverted position in the aforesaid space with its flange-portion, beveled as aforesaid on the top of its wider-end, extending between and contacting with the opposing side of the heads of the frog-point-forming rails, being tapered, as by planing, to conform to the space between them, and with the under side or base of its head-portion formed, as by swaging, to converge at corresponding angles toward its longitudinal center and thus conform to and seat and fit upon the inclined upper surfaces of the inner flanges of the said point-forming rails, with the center of the space between which the apical center of the bottom of said head coincides. The area of bearing-contact with the heads of the two point-forming rails of the edges of the flange of the interposed rail is not sufficiently extensive, because of the relative thinness of the flange, to afford to it stability under the stresses to which it is subjected in use; and the extent of bearing-surface of the head of the inverted rail upon the upper surfaces of the flanges at the opposing sides of the point-forming rails is insufficient to prevent the interposed rail from tipping under the said stresses and tending to spread apart the rails of the frog-point.

My invention overcomes the defects re-

ferred to of the described structure by the construction illustrated in the accompanying drawing, in which—

Figure 1 shows a plan view of a railway-frog embodying my improvement; Fig. 2 is an enlarged section on line 2, Fig. 1; Fig. 3, a view in end elevation of the heel-riser rail, showing the head and flange in their original condition by dotted representation, and by full lines the condition to which they are reduced for the purpose of my improvement; Fig. 4, a view of the same in side elevation, and Fig. 5, a plan view of the same showing the original transverse dimensions of the head and flanges and the rail-web or neck by dotted lines.

The frog shown, which is represented in Fig. 1 in position on its supporting-ties 6, comprises the usual main rails 7 and 8, the frog-point 9 formed of converging rails with a heel-riser 10 interposed between them, and filling-blocks 11 and 12 in the spaces between the main rails and the point; the parts being securely fastened together at intervals by transverse bolts 13.

The heel-riser 10 is an ordinary T-rail having one end of its head 14 swaged to form the inclined section 15 and expand it to the width between the point-forming rails at the heel of the frog, the sides of the head being planed down to taper them to a fit between the said rails; and the flanges 16 of the heel-riser are swaged to reduce them to the condition illustrated in Fig. 3, wherein their upper sides are horizontal and their under sides converge at similar angles to a central longitudinal apex coincident with the longitudinal center of the rail-neck 17. The bases of the flanges 16 are thus caused to conform to the inclinations of the tops of the inner flanges of the rails forming the frog-point, with the width of which they correspond so as to extend upon them up to the necks of said point-rails, being normally of that width at the end of the inclined section 15 and thence planed along their edges to taper them in conformity to the convergence of the point-forming rails.

The heel-riser, reduced to the described form, is interposed in upright condition into and fastened in its place between the point-forming rails of the frog, seating upon the full area of the adjacent flanges of those rails and abutting at their edges against the necks thereof, while throughout the greater part of its length the full depth of the head 14 finds

bearing against the opposing inner sides of the heads of the point-forming rails. Thus the heel-riser finds a stable seat at its flanges by covering such an extensive area of seating-surface, whereby any tipping tendency thereof under stresses against its head are resisted by the necks of the point-forming rails, and tendency to spread the latter under such stresses is resisted by the extensive area of frictional contact between the surfaces of the point-rail flanges and those of the flanges 16.

What I claim as new and desire to secure by Letters Patent is—

- 15 1. A heel-riser for a railway-frog, comprising a railway-rail having one end of its head formed with an expanded and inclined section, the sides of said head being tapered, and the flanges of said rail being tapered to 20 extend between the necks of the point-forming rails of the frog and conforming on their under side to the seat therefor formed by the upper surfaces of the flanges of said rails.
- 25 2. In a railway-frog, a heel-riser comprising a T-rail fitting at its head against and

conforming to the opposing sides of the converging heads of the point-forming rails, the flange of said riser extending between and conforming to the opposing sides of the converging necks of said rails and conforming to 30 and seating upon the opposing flanges of said rails, said riser having on one end of its head an expanded and inclined section.

3. In a railway-frog, a heel-riser fitting in the tapering space between the converging rails forming the frog-point, said riser consisting of an upright T-rail having its head expanded and inclined at the heel of the frog and thence tapered to its opposite end to conform to and bear against the opposing 40 sides of said converging rails, and having its flange tapered longitudinally and bent upwardly to fit against and conform to the necks of said converging rails and to conform to and seat upon the opposing flanges of said 45 rails.
